UNITED STATES PATENT OFFICE.

GUSTAV BUTZKE, OF ALPLAUS ROAD, NEW YORK, ASSIGNOR TO GENERAL ELECTRIC COMPANY, A CORPORATION OF NEW YORK.

ROTARY-SWITCH HANDLE.

Application filed June 4, 1921. Serial No. 475,035.

To all whom it may concern:

Be it known that I, GUSTAV BUTZKE, a citizen of the United States, residing at Alplaus Road, in the county of Schenectady, State of New York, have invented certain new and useful Improvements in Rotary-Switch Handles, of which the following is a specification.

The present invention relates to electric switches and more especially to the operating handles of rotary snap switches.

Rotary snap switches are usually provided with a removable cover enclosing all live parts and held in place by the operating handle having screw-threaded engagement with the switch shaft. In order to protect against removal of the cover and the resulting exposure of the live parts by children or persons unskilled in the art, it is necessary to provide means for locking the cover or the switch handle in place, so that they may not be removed except by those possessing the proper tools or the secret of the releasing manipulation thereof.

The object of my invention is to provide a simple, hardy and highly efficient switch handle that may not be detached by unskilled persons, which is not liable to become injured by rough or malicious usage and which may be manufactured at low cost.

One embodiment of the invention is shown in the accompanying drawing, in which:

Fig. 1 is a perspective view, with parts in section, of a rotary snap switch with the improved handle connected therewith; Fig. 2 is a similar view of the handle with the parts in different relative positions; Fig. 3 is a horizontal section of the handle; Fig. 4 is a bottom plan view thereof; and Fig. 5 is a sectional view of the handle.

The switch shown is an ordinary commercial form having a rotary pole piece 1 mounted on a rotary shaft 2 and connected therewith through a helical spring 3, the upper end of which is attached to a notched disk 4 fast on the shaft. The cover 5 is cup-shaped with a central aperture 6 and adapted to engage a shoulder of the switch base 7 at its lower end.

The switch handle 8 has a tapped hub member 9 adapted to pass freely through the central aperture 6 in the cover and be screwed upon the threaded upper end of the rotary shaft 2 until arrested in its advance

thereon by jamming against the spring seating disk 4. The external lower portion of the hub 9 is cylindrical, Fig. 2; the middle portion is hexagonal; the upper portion is cylindrical and at the junction between the central and upper portions is secured a radial shoulder or guide ring 10. The top has a longitudinal slot in which is fixed a bent leaf spring 11, the radially movable outer end of which constitutes a snap pawl.

The swivelled body portion 12 of the handle 8 is of insulating material moulded about a sheet metal cylinder 13 coaxial therewith and forming a metal walled chamber within the body portion. The body portion has its exterior surface knurled or roughened to provide a good hand hold and at its lower end is a cylindrical wall 14 adapted to bear at its lower edge against the top of the switch cover 5. The sheet metal cylinder 13 has two longitudinal internal grooves 15, Fig. 3, which provide ratchet shoulders with which the end of the leaf spring 11 normally engages. The lower end of the cylinder 13 is provided with two retaining flanges 16, Fig. 4, spun over the under side of a guide plate 17 having wings 18 disposed between the ends of the flanges 16 and serving to lock it against relative rotation therewith. The plate 17 has a central hexagonal aperture in which the lower portion of the hub 9 is free to move axially and angularly.

In order to insure that the handle shall press against the cover 5 to hold it in engagement with the switch base sufficiently firmly to prevent rattling and without danger of springing the cover 2 or producing excessive friction therewith, a helical spring 19 is disposed about the hub 9 and thrusting at its ends against the guide ring 10 and guide plate 17.

When it is desired to operate the switch, the handle 8 is turned clockwise and with it, by reason of the engagement of the outer end of the leaf spring 11 with one of the grooves 15, is also turned the hub 9 and the switch parts connected thereto. When the handle is rotated backwardly, the ratchet connection between hub and body members permits the latter to swivel freely on the former without tending to unscrew it from the shaft.

In case it is desired to disconnect the handle to permit the cover to be removed,

it may be locked against swivelling on its hub 9 by pulling upwardly thereon against the thrust of the spring 19 until the hexagonal middle portion of the hub is brought 5 into the hexagonal opening in the guide plate 17.

While I have shown and described the best form of embodiment of the invention, I do not desire to be restricted thereto.

13. What I claim as new and desire to secure by Letters Patent of the United States, is:—

15. A switch handle comprising a hub member having provisions for rotary attachment to a switch shaft, a radially movable pawl fixed upon said hub member, a chambered body member enclosing and movable longitudinally and rotarily about said hub member and pawl, longitudinal ratchet members on the chamber wall adapted 20 to be engaged by said pawl normally to prevent rotation of the body member in one direction on the hub member, and means for locking said hub and body members together upon the latter member being moved 25 longitudinally of the former member.

2. A switch handle comprising a hub member having provisions for attachment to a switch, a leaf spring fixed upon said hub and having a radially movable end, and a 30 swivelled body member having an axial chamber with ratchet shoulders on the wall thereof adapted to be engaged by the end of said leaf spring.

3. A switch handle comprising a hub 35 member having provision for threaded engagement with a switch shaft, a radially movable snap pawl fixed upon said hub member, an insulated metal cylinder freely surrounding said hub member and pawl and provided with internal longitudinal shoulders for engagement with said pawl upon 40 rotation of said cylinder in one direction, a spring normally acting to press longitudinally said hub member into said body member, and means to lock said hub and body members against rotation in both directions upon axial movement of the members 45 in opposition to said spring.

4. A switch handle comprising a hub 50 member adapted to be attached to a switch and provided with a radial shoulder, a radially movable snap pawl fixed upon said hub

member, a swivelled body member having a longitudinally grooved axial chamber in which said hub and pawl are disposed, a 55 guide plate secured to said body member at the lower end of said chamber, a spring thrusting against said guide plate and the radial shoulder on said hub member, and engaging means on said plate and said hub member to lock said parts against relative rotation upon the projection of said hub part therethrough in opposition to said spring.

5. A switch handle comprising a hub 65 member adapted to be attached to a switch and provided with a plain lower end and an adjoining polygonal portion, a leaf spring secured to the upper end of said hub member and having a radially movable free end, 70 a body member having a chamber with longitudinal shoulders on its inner wall adapted to be engaged by the free end of said leaf spring, a polygonally apertured plate fixed to said body member at the lower end of the 75 chamber, and a spiral spring engaging said guide plate and said hub member.

6. A switch handle comprising a hub member having provisions for attachment to a switch, a radially movable snap switch 80 pawl fixed upon said hub member, a swivelled body member having an axial chamber therein with a ratchet member on the wall thereof adapted to be engaged by said snap pawl, and means carried by the 85 said body which when the latter is moved axially engage the hub member and cause the body and hub member to move as a unit.

7. A switch handle comprising a hub member having provisions for attachment to a switch, a radially movable snap switch 90 pawl fixed upon said hub member, a swivelled body member having an axial chamber therein with a ratchet member on the wall thereof adapted to be engaged by 95 said snap pawl, and provisions for removing the body member from the switch which comprise a guide plate having an irregular central opening the walls of which engage the hub member when said body is moved 100 axially outward.

In witness whereof, I have hereunto set my hand this 3rd day of June, 1921.

GUSTAV BUTZKE.
